UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

FLUE COLLAR FOR GAS RANGES.

Application filed July 18, 1921. Serial No. 485,721.

To all whom it may concern:

Be it known that I, RUDOLPH HOFFMAN, a citizen of the United States, residing at Kankakee, in the county of Kankakee and 5 State of Illinois, have invented certain new and useful Improvements in Flue Collars for Gas Ranges, of which the following is a specification.

The invention relates to flue collars for 10 gas ranges, and has for its aim the provision of such a device which is especially adapted to lessen the cost of crating the range for shipment as well as minimize loss by injury thereto in shipment.

15 Flue collars for gas ranges as ordinarily constructed and arranged project upwardly from the stove top or frame for the purpose of receiving the lower end of the flue pipe. By reason of this arrangement of the collar, 20 it becomes necessary in crating the stove for shipment to make the crate large enough or otherwise especially construct it to protect this upstanding collar.

The principal object of the present invention is to provide a flue collar which extends downwardly from the upper surface of the stove top and thus overcomes the difficulties referred to.

A further object is to provide a flue collar 30 of advantageous construction and one which is especially adapted to prevent the user of the range from entirely closing the collar when the range is used without attachment to a flue.

35 The objects of the invention thus generally stated are attained by the construction and arrangement illustrated in the accompanying drawing forming part hereof, but it is to be understood that the invention is 40 not limited to the construction and arrangement shown in the single embodiment which I have selected for the purposes of illustration but that various changes may be made in construction, form and arrangement 45 without departing from the spirit and scope of the invention as expressed in the appended claims.

Figure 1 of the drawings is a fragmentary perspective view of the top of the stove 50 equipped with my improved flue collar. Fig. 2 is a fragmentary vertical sectional view illustrating the collar as a means for preventing the opening in the frame from being closed when the flue pipe is not attached. Fig. 3 is a top plan view of the

rear frame member and the flue collar attached thereto.

In the drawings, 4 designates the top of a gas range having a rear frame member 4^a. The latter has an aperture 5 therein in 60 which the flue collar is supported.

The collar proper is designated by the numeral 6 and is of a shape corresponding to the aperture 5, which is herein made elliptical in form. This collar is preferably 65 formed of sheet metal and gradually decreases in size toward its lower end, which is provided with an inturned flange 7 upon which the lower end of the flue pipe *a* (shown in dotted lines in Fig. 2) is adapted 70 to seat. Near the upper end of the collar there is provided an annular out-turned bead 8 between which and the out-turned flange 9 at the extreme upper end of the collar is formed a groove 10 for receiving the rear 75 frame member at the edge of the opening 5. The bead 8 is of larger diameter than the aperture 5 and is adapted to yield inwardly to permit the collar to be mounted on the frame member. By this means the collar 80 is rigidly secured in operative position in the stove top, and by reason of the peculiar shape of the collar, being somewhat larger at its upper end, the flue pipe is capable of being easily inserted thereinto and is held 85 by a wedging engagement with the collar.

It sometimes happens that gas ranges are used without making provision for the escape of the gases of combustion through a flue. In such instances the flue pipe is not 90 attached to the flue collar and the housewife or other user may attempt to close the collar by means of a flat plate, dish or the like. To prevent such closure of the aperture through the collar, I provide means comprising a pair of coacting members 11 and 11^a together constituting a spider fitted 95 within the collar and having rounded upper edges projecting above the horizontal plane in which the upper end of the collar lies. To provide for such interengagement of the members 11 and 11^a they are respectively notched at upper and lower edges as at 12; and to hold the device in fixed relation with reference to the collar, the opposite edges 100 of the members are slotted near their lower ends as at 13 to receive the inturned flange 7, the members being made of sufficient length to extend somewhat below the lower end of the collar for this purpose. In the 110

operation of assembling the device in the collar, the portions 14 of the members below the notches 13 are bent inwardly so as to pass the flange 7 and then outwardly into holding engagement with the latter as shown in Fig. 2.

It will be seen that I have provided a support for a flue pipe, which is of an exceedingly simple construction and is furthermore of a practical character. It is capable of being quickly and easily secured to the stove top, and simple means is provided for preventing a user through ignorance from closing the aperture intended for the outlet of the gases of combustion when the flue pipe is not employed.

I claim as my invention:

1. In a gas range, the combination with a frame member having an aperture therein, 20 of a flue collar constructed of sheet metal and bent at its upper end into holding engagement with the frame member, the lower end of the collar having an inturned flange,

and means operatively engaging said flange and projecting above the collar while permitting of the passage of gases through the collar. 25

2. In a gas range, the combination of a frame having an aperture therein, a flue collar depending into said aperture, and a spider secured within said collar and projecting above the plane of the upper end thereof, said spider comprising a pair of interengaging members one of which is detachably secured to the collar. 30 35

3. In a gas range, the combination of a top having an aperture therein, a flue collar secured at the upper end of said aperture and extending downwardly therefrom, and means adapted to prevent the complete closure thereof by an article placed upon the upper end over the same when a flue pipe is not in use. 40

In testimony whereof, I have hereunto set my hand.

RUDOLPH HOFFMAN.
